Bernard Raphael Glukes
INVENTOR.
BY

UNITED STATES PATENT OFFICE

156,823

KITCHEN UTENSIL RACK

Bernard Raphael Glukes, North Hollywood, Calif.

Application September 16, 1948, Serial No. 148,598

Term of patent 7 years

(Cl. D44—29)

To all whom it may concern:

Be it known that I, Bernard Raphael Glukes, a citizen of the United States, residing at North Hollywood, in the county of Los Angeles and State of California, have invented a new, original, and ornamental Design for Kitchen Utensil Racks, of which the following is a specification, reference being had to the accompanying drawing, forming part thereof.

Fig. 1 is a perspective view of a kitchen utensil rack, showing my new design;

Fig. 2 is a top plan view; and

Fig. 3 is an end view thereof.

I claim:

The ornamental design for a kitchen utensil rack, as shown.

BERNARD RAPHAEL GLUKES.
